(57) **CLAIM**

The ornamental design for a case, as shown and described.

DESCRIPTION

FIG. 1 is a front view of a case showing my new design wrapping an environmental electronic device;

FIG. 2 is a right side view thereof wrapping the environmental electronic device; and,

FIG. 3 is a rear view thereof wrapping the environmental electronic device.

The broken lines represent an environment of use and portions of the case and form no part of the claim. The boundary lines on FIG. 3 represent the boundary of the claim.
